Inventor:

UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC-LAMP SOCKET.

1,215,141.

Specification of Letters Patent.

Patented Feb. 6, 1917.

Application filed September 14, 1916. Serial No. 120,156.

To all whom it may concern:

Be it known that I, GILBERT W. GOODRIDGE, a citizen of the United States of America, and residing at Bridgeport, in the county of Fairfield and State of Connecticut, have invented a certain new and Improved Electric-Lamp Socket, of which the following is a specification.

My invention relates to electric lamp sockets and particularly to the interior construction of the socket, the object of my invention being to provide an improved construction of the insulating body with relation to the switch mechanism and by which the switch frame is held rigidly in position in said body.

Referring to the accompanying drawings, Figure 1 is a vertical section through a lamp socket in which my invention is embodied in one form;

Fig. 2 is an inverted plan of one of the insulating buttons which form the body of the socket;

Fig. 3 is a plan of the second insulating button; and

Fig. 4 is a section on the lines 4—4, Fig. 3.

The present invention relates particularly to the type of socket shown in my co-pending application Serial No. 763,604, and is 30 designed to afford a more secure mounting of the switch frame on the insulating body to prevent any tendency of the latter to swivel or become loose by reason of repeated actuation of the switch mechanism. 35 The socket comprises the usual metallic casing having a cap 10 and shell 11 with insulating lining 12 and thumb piece 13 projecting through the casing to operate the switch mechanism contained therein. A

40 pair of insulating buttons 14 and 15, normally secured together by bolts passing through holes 16 and 17, are recessed on their meeting faces to afford a switch chamber 18 within which the switch mechanism

45 is mounted. As in my previous construction, the switch terminals 19 and 20 are carried by the lower button 15 and the circuit is completed between the same by the oscillating switch piece 21. The switch mechanism

50 is mounted upon a frame 22 having a base 23 with end standards 24 and 25 and side wings 26 and 27 between which the operating parts are arranged. The switch frame is secured to the lower button 15 by means

of a screw 28 piercing the lower button 15 and taking into a tapped hole in the base 23 of the frame. After repeated actuation of the switch mechanism there is a tendency of the frame to work loose from the screw. While there is no danger in my previous construction, that the switch frame will work loose to an extent such that the mechanism will become deranged, a feeling of insecurity is produced which renders the socket objectionable. The present invention provides means to overcome this undesirable feature.

For the purpose mentioned, I have so formed the buttons 14 and 15 with respect to the frame that the latter is now braced against the buttons at several points, each of which serves to maintain the frame rigid and to take up the various strains to which the frame is subjected on the operation of the switch mechanism. As shown in the accompanying drawings there are three points of engagement. One of these is a rib 29 formed in the button 15 in line with the hole 30 through which the securing screw 28 passes and taking into a channel 31 formed in the base 23 of the frame at a corresponding point. A second point of engagement is afforded by a shoulder 32 formed on the upper button 14 and projecting down into the switch chamber 18 and into engagement with the ends of the extended arms 33 on the sides of the switch frame which form the stops limiting the upward throw of the oscillating switch piece 21. The third point of engagement is afforded by a boss 34 projecting upward into the switch chamber from the lower button 15 and lying between the side wings 26 and 27 of the frame. The boss 34 is spaced from the sides of the chamber 18 substantially the thickness of the metal of the frame so that the wings 26 and 27 lie snugly in the channels afforded between the opposite sides of the boss 34 and the body of the lower button 15. It also bears against end standard 25.

The engagement of the frame in this manner by the buttons at the three points mentioned affords a very rigid bracing and there is no possibility whatever of the frame working loose under any operating conditions.

Various other ways of bracing the frame will readily occur to those skilled in the art

and I do not limit myself to the precise construction shown, which may be variously modified without departing from what I claim as my invention.

5 I claim as my invention:—

1. An electric lamp socket having an insulating body, a switch frame having a base mounted thereon, means for securing said frame to the body, and an interengaging rib and groove on said body and base to prevent swiveling of said parts with relation to each other.
2. An electric lamp socket having an insulating body, a switch frame mounted thereon and having a base and a pair of side uprights, means engaging said base to secure the latter on the body and a boss on said body engaged between the said frame uprights to prevent relative movement of the frame on the body.
3. An electric lamp socket having an insulating body, a switch frame mounted thereon and having an end upright and a pair of side uprights extending beyond said end upright, in combination with a boss on said body bearing against said end upright and lying between said extended side uprights, for the purpose described.
4. An electric lamp socket having a chambered insulating body, a switch frame having a base mounted on the bottom of said chamber, side uprights on said base and extending beyond the end of the latter, and a ledge in the top of said chamber against

which the extended ends of said side uprights abut, for the purpose described.

5. An electric lamp socket having a chambered insulating body, a switch frame and means for mounting the same on the bottom of said chamber, an end upright and a pair of side uprights embracing and extending beyond said end upright and a boss engaged between said side uprights beyond said end upright.

6. An electric lamp socket having a chambered insulating body, a switch frame having a base and means engaging said base for securing the frame in the chamber of said insulating body, end and side uprights on said frame and means engaging said end and side uprights to brace the frame in said chamber.

7. An electric lamp socket having a chambered insulating body, a switch frame having a base and means engaging said base for securing the frame in the chamber of said insulating body, end and side uprights on said frame and means engaging said base and said end and side uprights to brace the frame in said chamber.

In testimony whereof I have signed my name to this specification, in the presence of two subscribing witnesses.

GILBERT W. GOODRIDGE.
